Frederick J. Lau,

By Drake & Co. Atty's.

UNITED STATES PATENT OFFICE.

FREDRICK J. LAU, OF NEWARK, NEW JERSEY.

LATCH.

SPECIFICATION forming part of Letters Patent No. 451,638, dated May 5, 1891.

Application filed January 31, 1891. Serial No. 379,768. (No model.)

To all whom it may concern:

Be it known that I, FREDRICK J. LAU, a citizen of the United States, residing at Newark, in the county of Essex and State of New Jersey, have invented certain new and useful Improvements in Latches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates more especially to refrigerator-latches, and has for its object to secure certainty and ease of action and simplicity and economy in the cost of construction.

The invention consists in the improved latch and in the arrangement and combination of the several parts thereof, as herein shown and described, and finally pointed out in the claims.

Referring to the accompanying drawings, in which similar letters of reference indicate corresponding parts in each of the several figures where they occur, Figure 1 represents in front elevation a broken-off portion of a refrigerator-door and door-jamb and my improved latch, &c., attached thereto. Fig. 2 represents a back plan view of the latch; and Fig. 3, a similar view, the back plate being removed and exposing the working parts of the

latch in the case. Fig. 4 is a longitudinal transverse section taken through line *x* of Fig. 1, and Fig. 5 is a vertical transverse section through line *y* of Fig. 2. Figs. 6 and 7 represent plan and end views, respectively, of the catch-plate; and Figs. 8 and 9 represent side and rear elevations, respectively, of the catch-bolt and its operating-arm, &c.

In said drawings, A and B, Figs. 1 and 4, indicate, respectively, a broken-off portion of a refrigerator-door and the door-jamb.

C indicates the latch-case, which has a front projection C'.

d indicates a stationary knob, and *e* a bolt, which passes through the knob, case, and door, and is secured by a nut *e'* inside of the door, thereby aiding to hold the parts together and to said door. The knob, however, may be

solid and have a shank long enough to serve the purpose of the bolt and the latter be dispensed with, if desired.

55

Within the case C is arranged a sliding catch-bolt *f*, which is provided at the front end with a hook-catch *g*, which projects through the back plate C' of the case to engage with the catch-plate *h* when in a locked position, as indicated in Fig. 4. Said hook-catch is slightly tapering toward the end to facilitate its free entrance into the opening in the catch-plate *h* and to secure automatic action, as will be understood. Said catch-bolt at its opposite end is provided with an operating-arm *f'*, which projects through the outside of the case to within convenient reach from the knob, so that it may be grasped in connection therewith and the latch-bolt be operated by a slight pressure thereon to release the catch, as will be understood, the catch being thrown into locking engagement automatically by means of the incline on the hook-catch and a spring *i*, one end of which is seated 70 against a hub *j*, projecting from the case-plate and the other against a cross-bar *k* in the skeleton portion or shank of the catch-bolt. The said operating-arm moves through a slot 75 *l* in the case-plate, as indicated in Figs 3 and 4. 80

The case is provided with hubs *m* and *n*, upon which the back plate rests. The knob-shank or bolt *e* also passes through said hub *m*, and a screw *o* engages in a threaded socket in the hub *n* to hold said back plate in position, as indicated in Figs. 2 and 3.

The slotted catch-plate *h*, Figs. 1, 4, 6, and 7, is adapted to be secured upon the outside and inner edge of the door-jamb, suitable screw-holes *s* being provided therefor.

90

It will be noticed that the portion C' of the case projects beyond the front edge of the door and overlaps the jamb, as indicated in Figs. 1 and 4, and that the latch-bolt is entirely concealed from view when the door is closed.

Having thus described my invention, what I claim, and desire to secure by Letters Patent of the United States, is—

1. The improved latch for refrigerators 100 herein described and shown, consisting of the case C C', provided with the slot *l*, hubs *j*, *m*, and *n*, a stationary non-rotating knob, a latch-bolt provided with the hook-catch *g*, project-

ing through the back plate, the operating-arm f' , rigidly secured to said latch-bolt and projecting through the front of the case, and a cross-bar k , and a spring seated against 5 said hub j and cross-bar k , said parts being arranged and operating as described, and for the purpose set forth.

2. In a latch, the combination, with the stationary non-rotating knob, of a latch-bolt provided with a backwardly-projecting hook- 10 catch adapted to engage a catch-plate beneath the lock-case, and an operating-arm rigidly

connected to said latch-bolt and projecting outside of said case near said knob, said parts being arranged to operate as described, and 15 for the purposes set forth.

In testimony that I claim the foregoing I have hereunto set my hand this 21st day of January, 1891.

FREDRICK J. LAU.
